UNITED STATES PATENT OFFICE.

WILLIAM STEPHENSON, OF HAMILTON, ONTARIO, CANADA.

POST-HOLE AUGER.

SPECIFICATION forming part of Letters Patent No. 269,548, dated December 26, 1882.

Application filed July 5, 1882. (No model.) Patented in Canada March 12, 1881, No. 12,494.

To all whom it may concern:

Be it known that I, WILLIAM STEPHENSON, of Hamilton, in the county of Wentworth, in the Province of Ontario, Dominion of Canada, 5 have invented certain new and useful improvements in Post-Hole Augers; and I do hereby declare that the following is a full, clear, and exact description of the construction and operation of the same, reference being had to the annexed drawings, forming part of this specification.

Figure 1 represents a perspective view of my invention with the stock broken away; Fig. 2, an inverted perspective view of Fig. 1; 15 Fig. 3, a vertical central section.

This invention relates to improvements in augers for boring post-holes in the ground, and has for its object to improve the details of construction and provide a ground-auger; 20 which is simple in construction and very efficient in operation.

The object of my invention I accomplish by the construction and union of parts illustrated in the accompanying drawings, which 25 I will proceed to describe in detail, afterward pointing out in the claims the specific improvements which constitute my invention.

The letter A indicates the tubular stock, composed of gas-pipe screw-threaded at one 30 end, as at A', to screw into the center or hub C of the disk C', which is threaded to receive it; and B, the tubular handle, secured to the stock. The disk C' is made of malleable iron, provided with two openings, b b, each faced 35 with a steel bit or cutter, D, riveted to one side of each opening. The steel bits or cutters D are each constructed with a cutting-edge, e, turned up nearly at right angles to the bit to form a sharp cutting-edge to cut the 40 earth clean in boring the post-hole.

The letters d d indicate the lateral ventilating-openings in the hub C and under the disk to supply air through the tubular handle and stock to the under side of the cutting-disk; 45 and E indicates the screw-point, having threaded shank E', which is screwed into the under side of the hub of the disk, which hub is threaded to receive it. This point is of mal-

leable cast-iron, and is constructed with direct tapers specially adapted for the purpose of 50 rapid and easy earth-boring; and it will be seen that the said screw tapers gradually on the outside from the base to the point, the central or grooved portion from g g and the thread h being constructed to gradually taper from the 55 base at h to a point, e, at the extreme end. This form of screw-point I have found by experience possesses efficient working qualities, and is capable of boring successfully in the hardest ground with less labor and more speed 60 than can be done with other post-hole augers.

I am aware of Letters Patent No. 160,648, and do not wish to be understood as claiming what is therein shown and described. My construction differs from it in that I form the 65 transverse air-openings d d directly through the under part of the hub C, and I thereby avoid drilling lateral holes in the screw-point, which would weaken and render it liable to become easily fractured or broken.

Having thus described my invention, what I 70 claim is—

1. A ground-auger consisting of a radially-slotted disk formed integral with a hollow hub, which projects from its opposite sides, that 75 part of the hub on the under side of the disk being transversely perforated and receiving the screw-point, and the other part of the hub on the upper side of the disk receiving the hollow stem having the hollow handle, substantially as described.

2. A ground-auger composed of a radially-slotted disk formed integral with a central hollow hub, which projects from its opposite sides, each projecting part of the hub being interiorly 85 screw-threaded, and that part of the hub formed on the underside of the disk being transversely perforated, substantially as and for the purpose described.

Dated at Hamilton, Ontario, Dominion of 90 Canada, this 29th day of March, 1882.

WM. STEPHENSON.

In presence of—

JULIEN R. SEAVEY,
WM. BRUCE.
